(57) **CLAIM**

The ornamental design for dental model base quadrant with a plurality of indexing pins, as shown and described.

DESCRIPTION

FIG. 1 is a front perspective view of a dental model base quadrant with a plurality of indexing pins showing my new design;

FIG. 2 is a rear perspective view thereof;

FIG. 3 is a top plan view thereof;

FIG. 4 is a left side elevation thereof;

FIG. 5 is a right side elevation thereof;

FIG. 6 is a rear elevation thereof;

FIG. 7 is a front elevation thereof;

FIG. 8 is a rear perspective view thereof;

FIG. 9 is a front perspective view of a modified embodiment of the design shown in FIGS. 1 through 8;

FIG. 10 is a rear perspective view thereof;

FIG. 11 is a top plan view thereof;

FIG. 12 is a left side elevation thereof;

FIG. 13 is a right side elevation thereof;

FIG. 14 is a front elevation thereof;

FIG. 15 is a rear elevation thereof; and,

FIG. 16 is a rear perspective view thereof.

The broken line showing of environment in the figure drawings is for illustrative purposes only and forms no part of the claimed design.
